(57) **CLAIM**

The ornamental design for a stand for monitor, as shown and described.

DESCRIPTION

FIG. 1 is a front perspective view of a stand for monitor showing our new design;

FIG. 2 is a front elevation view of FIG. 1;

FIG. 3 is a rear elevation view of FIG. 1;

FIG. 4 is a left side elevation view of FIG. 1;

FIG. 5 is a right side elevation view of FIG. 1;

FIG. 6 is a top plan view of FIG. 1;

FIG. 7 is a bottom plan view of FIG. 1;

FIG. 8 is a front perspective view of the stand for monitor in which a monitor and a phone are provided in dot-dash broken lines to illustrate an example environment;

FIG. 9 is a rear perspective view of the stand for monitor in which a monitor and a phone are provided in dot-dash broken lines to illustrate an example environment;

FIG. 10 is a front perspective view of a second embodiment for a stand for monitor, showing our new design;

FIG. 11 is a front elevation view of FIG. 10;

FIG. 12 is a rear elevation view of FIG. 10;

FIG. 13 is a left side elevation view of FIG. 10;

FIG. 14 is a right side elevation view of FIG. 10;

FIG. 15 is a top plan view of FIG. 10;

FIG. 16 is a bottom plan view of FIG. 10;

FIG. 17 is a front perspective view of the stand for monitor in which a monitor and a phone are provided in dot-dash broken lines to illustrate an example environment; and,

FIG. 18 is a rear perspective view of the stand for monitor in which a monitor and a laptop computer are provided in dot-dash broken lines to illustrate an example environment. The broken lines in the figures form no part of the claimed design.

The dot-dash broken lines in the drawings depict of the monitor, the phone and the laptop computer that form no part of the claimed design.

1 Claim, 18 Drawing Sheets
